UNITED STATES PATENT OFFICE.

GEORGE GROSS, OF BUFFALO, NEW YORK.

IMPROVEMENT IN WATER-WHEELS.

Specification forming part of Letters Patent No. 44,302, dated September 20, 1864.

To all whom it may concern:

Be it known that I, GEORGE GROSS, of Buffalo, in the county of Erie and State of New York, have invented new and useful Improvements in Water-Wheels and Running the Millstones on the same Shaft; and I do hereby declare that the following is a full and exact description thereof, reference being had to the accompanying drawings, and to the letters of reference marked thereon, making a part of this specification.

The nature of my invention consists in a hollow perforated and vertical shaft, in combination with the adjustable socket and bearing, with the millstones on top of the shaft, oil-tube for the toe, also a water-guide on the inside of the scroll.

To enable others to make and use my invention, I will proceed to describe its construction and operation.

Figure 1 represents a side elevation. Fig. 2 shows the shape of the scroll. Fig. 3 represents the water-wheel; Fig. 4, the shaft and sleeves; Fig. 5, the upper part of shaft or spindle, with its socket; Fig. 6, the square box in which the socket operates and is adjusted.

A represents the shaft or spindle, upon the top of which I propose to place and fasten the millstones B B. The lower millstone B is stationary, and rests upon a cross-beam, C. This beam is supported at each end by uprights D. The spindle A operates near the center of the beam C, and rests in the top of a lower shaft, E. The second cross-beam or bridge-tree, G, is adjustable, and also rests in uprights D in slots in the uprights, so as to be adjusted in raising and lowering the upper millstone. This bridge-tree G has an adjustable square-sided box, H, concave in the center, with two set-screws, I—one at each side—and four apertures, J, at the opposite sides, for the purpose of inserting keys to move the box H and adjust it to the right or left side.

The set-screws are for the purpose of adjusting the inside adjustable socket and bearing, K, which is slightly concave at top and convex underneath, with two semicircular sides, L, in which the set-screws I operate, for the purpose of adjusting the socket K back or forward in opposite directions, to the keys, while the semicircular sides L are allowed to

rock or play from right to left, for the purpose of keeping the spindle in its true vertical position and preventing the weight of the millstone from resting on the wheel or toe, so as to avoid the raising or lowering the wheel M or step N in raising or lowering the millstone. The semicircular sides L rest and play in corresponding grooves of the box H. The socket K is concave at top, so as to hold oil sufficient to lubricate the socket on the under side of the collar P, which collar is permanently tight on the spindle A, and is made of steel or hard metal, the oil being conducted to the under side of the collar P and spindle A by small channels or ducts in the socket and holes in the collar P. The socket K is made of cast-iron, and the center of the socket, near the collar of the spindle, is to be of chilled iron or steel, or of suitable metal, and filled with Babbitt or other suitable metal around the spindle A. The socket K is thus a double adjustable bearing—viz: one for the collar P on the spindle, and the other the inside of the socket around the spindle. The collar P is concave next to the spindle, and the center of the socket K is slightly raised to prevent the escape of the oil. The spindle A is square at the lower end, and fits into the top of the upper end of the hollow shaft E, so as to be adjustable in raising or lowering the millstone. The shaft E is hollow, and has apertures R above the wheel and just below the upper cap, S, and the bottom of the water-wheel M, for the purpose of letting the air pass in or out of the scroll U and the wheel M, as required. This hollow-shaft E has an oil-tube, V, extending through the hollow from above the wheel M into the concavity of the lower end of the shaft E, (and around which and the step or toe N Babbitt or other metal is put,) for the purpose of lubricating the step N and concave.

X are two sleeves on the hollow-shaft E—one at top and the other at bottom of wheel M—for the usual purpose of keying and truing the wheel and raising the wheel without disturbing the shaft or gearing.

Z is the cylinder of the wheel M, having slatted apertures a at top, for the purpose of getting the hands in to fasten or unfasten the bolts and for filling in or removing gravel to form a balance-wheel, and the top has a flange that projects over the cylinder the width of the

buckets *b*. The flange prevents the pressure and friction of the water against the upper cap, *S*, of the wheel, and the cap prevents the leakage of water above. The upper one-half of the bucket is straight, and sets onto the cylinder *Z* square and perpendicular. The back part is incline, and the lower half is angular. The buckets *b* are bolted onto the cylinder *Z* and nutted on the inside of the cylinder, so that the face and back part of the buckets are left smooth, free from bolt-heads or nuts and backlash of water. I make the buckets—say, for instance, on a medium-sized wheel—that is, two feet in diameter and the depth of the cylinder twelve inches, the upper half and perpendicular face of the buckets eight inches in length, and the incline or back part three inches wide at top. The length of the lower part of the bucket is also eight inches, extending to the lower part of the cylinder, including the thickness of the bucket, while the width of the bucket from top to bottom is three inches.

c represents the mouth of the scroll *d*, which has a square rim, *e*, slightly flaring, to admit a spout, giving a close joint and smooth inner surface. The scroll *d* has a lower and narrow rim, *g*, beneath, the same size of the inside of the scroll, for the purpose of confining and contracting the water so as to prevent its too free discharge, that the water may have a continuous pressure upon the lower part of the bucket as well as the upper part, and prevent the pressure or obstruction of the wheel from the

outside. On the inside of the scroll *d* an angular or inclined projection, *f*, near the terminus of the scroll, forms a narrower or shorter space between the scroll and the wheel *M*, which is a water-guide and cut-off, directing the water downward to the lower corner of the throat of the scroll, and secures all the weight and pressure of the water upon the lower end of the buckets of the wheel as a motive power. The water strikes the bucket three-fourths its width, and the lower half of the bucket extends from one-sixth to one-eighth round the cylinder.

What I claim as my invention, and desire to secure by Letters Patent, is—

1. The arrangement and combination of the hollow perforated and vertical shaft, with its collar *P*, and its cavity at the lower end filled with Babbitt or other metal, its adjustable socket *K*, oil-tube and sleeves *X*, and millstones at top of shaft, when arranged and combined as herein described, and for the purposes set forth.

2. The construction and combination of the adjustable socket *K*, with its box *H*, as described, and for the purposes set forth.

3. The inclined projection *f* on the inside of the scroll, for the purpose set forth.

4. The angular construction of the buckets *b* of the wheel, as herein described.

GEORGE GROSS.
